*Primary Examiner—A. Hugo Word**Assistant Examiner—Doris V. Coles**Attorney, Agent, or Firm—Hugh E. Smith***[57]****CLAIM**

The ornamental design for a holder for welding rods, as shown and described.

DESCRIPTION

FIG. 1 is a front elevational view of the holder for welding rods showing my new design;
FIG. 2 is a rear elevational view thereof;
FIG. 3 is a left side elevational view thereof;
FIG. 4 is a right side elevational view thereof;
FIG. 5 is a top plan view thereof;
FIG. 6 is a bottom plan view thereof; and,
FIG. 7 is an isometric view thereof.

*FIG. 1**FIG. 2*FIG. 3
